United States Patent Office.

SAMUEL SAILOR, OF PHILADELPHIA, PENNSYLVANIA, ASSIGNOR TO FRANCIS BUCK-WALTER AND COMPANY, OF ROYER'S FORD, PENNSYLVANIA.

Design No. 2,680, dated June 18, 1867; antedated June 4, 1867.

DESIGN FOR A COOK'S STOVE.

The Schedule referred to in these Letters Patent and making part of the same.

TO ALL WHOM IT MAY CONCERN:

Be it known that I, SAMUEL SAILOR, of the city of Philadelphia, and State of Pennsylvania, have invented or produced a new and original Design for a Cook's Stove, of which the following is a full, clear, and exact description, reference being had to the accompanying drawing, making a part of this specification.

This design consists of the ornamental configurations shown on the front edge A of the top plate; on the front plate B; on the front doors C C; on the side doors or panels D D; and on the corners E E and F F, together with the ornamental moulding G on the edge of the hearth-plate H.

What I claim as my invention, and desire to secure by Letters Patent, is—

The ornamental design for a cook's stove, herein set forth and shown.

SAMUEL SAILOR.
